ATTORNEY

UNITED STATES PATENT OFFICE

161,309

BRACELET OR SIMILAR ARTICLE

Marcel Boucher, Eltingville, N. Y.

Application September 20, 1950, Serial No. 12,271

Term of patent 3½ years

(Cl. D45—4)

To all whom it may concern:

Be it known that I, Marcel Boucher, a citizen of the United States of America, residing at Eltingville, in the county of Richmond and State of New York, have invented a new, original, and ornamental Design for a Bracelet or Similar Article, of which the following is a specification, reference being had to the accompanying drawing, forming part thereof.

Fig. 1 is a top plan view of a bracelet, showing my new design; and

Figs. 2 and 3 are side elevational views thereof in open and closed positions, respectively.

I claim:

The ornamental design for a bracelet or similar article, as shown.

MARCEL BOUCHER.
